UNITED STATES PATENT OFFICE.

THOMAS SCHOCK, OF MONTELLO, NEVADA.

HORSE-COLLAR.

1,157,425.

Specification of Letters Patent. Patented Oct. 19, 1915.

Application filed August 5, 1915. Serial No. 43,762.

To all whom it may concern:

Be it known that I, THOMAS SCHOCK, a citizen of the United States, and a resident of Montello, in the county of Elko and State of Nevada, have invented a certain new and useful Improvement in Horse-Collars, of which the following is a specification.

My invention is an improvement in horse collars and the invention has for its object to provide a collar of the character specified, capable of adjustment to fit necks of different size, and wherein the collar is composed of a rigid frame, having a cushion engaging surface and provided with an inflatable inner lining, and permitting to dispense with the use of hames.

In the drawings: Figure 1 is a front view of the collar; Figs. 2 and 3 are sections on the lines 2-2 and 3-3 respectively, of Fig. 1, each looking in the direction of the arrows adjacent to the line, and Fig. 4 is a front view of the inner lining.

The present embodiment of the invention is composed of three sections, a top or neck section and two similar side sections. The top section is rabbeted, as shown, and is composed of a shell 1 of rigid material, as for instance metal, the said shell being open on its inner side, and a casing 2 of leather or the like is arranged within the shell, the said casing being circular in cross section and tubular, as shown.

The section 1-2 is arched to fit the top of the horse's neck, and a strap 3 is secured to the front thereof, by means of rivets 4 or the like, intermediate the ends of the strap, and the strap is curved to fit the curve of the neck-piece, the ends of the strap being left free.

The side sections are similar, each consisting of a rigid shell 5, of metal or the like, open at its inner side, and a casing 6 of flexible material, as for instance leather or the like is arranged within the shell, the casing being approximately cylindrical in cross section, and hollow, as shown more particularly in Fig. 3.

The arrangement of the shells 1 and 5 is such that the flexible casings 2 and 6 connected therewith extend beyond the edges of the said sections at the inner sides of the sections, to engage directly the horse's neck, and these casings extend far enough beyond the free edges of the shells to prevent the said shells from contacting with the neck

of the horse upon which they are used. The front edge of each of the shells 5 is extended and bent upon itself to form a cylindrical extension 7 at the front of the section, the said extension extending from the upper 60 end of each of the sections 5-6 to the lower inner end thereof.

It will be noted from an inspection of Fig. 1, that the lower end of each of the sections 5-6 is bent inwardly at approximately a right angle to the body portion of the section, and these angular portions are adapted to extend beneath the horse's neck and to be connected to hold the collar in place on the horse.

The cylindrical extensions 7 are open at their upper ends to form sockets which are designed to receive cylindrical pins 8 on the upper section 1-2. Each of these pins is hollow as shown, and of cylindrical form, and each pin has a lateral extension 9 at its upper end which laps upon the outer face of the shell 1 of the upper section at the front of the collar, and is secured thereto by rivets 10 or the like. The pins 8 are so arranged with respect to the section 1, that each pin will extend beyond the end of the section, a little more than half the length of the pin, as shown in Fig. 1. The pins are as before stated, at the front and at the inner side of the section, the pins being at the front inner edge of the shell 1. These pins, as before stated, are intended to engage within the upper ends of the extensions 7, and set screws 11 are threaded through bosses 12 on the extensions at the upper end thereof, to engage the adjacent pin, to prevent disengagement thereof, and to hold the pin in adjusted position with respect to the socket.

A buckle 13 is secured to each of the sections 5-6 just below the set screws 11, and at the front of the section. Each buckle 13 is connected to the shell 1 by a tab 14 of leather or the like, which is riveted to the shell, and the buckles are adapted to be engaged by the free ends of the strap 3, and the said ends have openings as shown for connection with the buckle.

The angular portions of the sections 5-6 are connected by a bolt, comprising a head 15 polygonal in cross section, and oppositely threaded portions 16 on opposite sides of the head. A nut 17 is connected with each of the sections 5-6 at the free end of the angular portions.

lar portion, each of the nuts being on the extension 7, and the nuts arranged with their openings in alinement.

The nuts are internally threaded in opposite directions, and it will be evident that when the bolt 15—16 is turned, the lower ends of the sections 5—6 may be drawn toward or from each other, to adjust the collar to the neck of the horse.

16 A clip 18 is arranged on the front of each of the sections 5—6, each clip being secured to the shell near the junction of the angular portion with the body. These clips are for connection with the tugs or traces, and from the clips the tugs or traces are passed rearwardly over the rigid shell.

17 A lining or inner tube 19 is arranged within the casings 2 and 6, the said inner tube as shown in Fig. 4, being of a size to extend 20 from the free end of the angular portion through one side section, through the neck section, and through the other side section to near the free end of the angular portion. The tube is shaped to fit and fill the casings 25 2 and 6, and at one end the tube is provided with a valve 20 of the usual construction, for permitting this tube to be filled with fluid under pressure.

18 In use, the inner tube 19 is filled with compressed air, thus expanding the casings 2 and 6, and holding the casings well extended beyond the shells 1 and 5 at the inner sides of the section. In order to adjust the collar to the horse's neck, the set screws 11 30 may be loosened to permit the side sections to move downwardly with respect to the neck section, until the angular portions at the lower ends of the side sections will fit smoothly under the neck of the horse. The 35 bolt 15 is then turned to draw the side sections toward each other, until the collar fits smoothly on the horse's neck. The extensions 7, the pins 8 and the metallic shells 1 and 5 stiffen and reinforce the collar, so that 40 no hames are needed. In addition, the soft 45 cushions formed by the casings 2 and 6 prevent any chafing or injury to the horse's neck.

50 Whenever the inner tube becomes lax it may be inflated. The strap and the buckles 13 assist in holding the sections in proper position with respect to each other, and in addition they prevent entire displacement of the sections 5 during adjustment of the 55 pins 8 in the extensions 7.

When it is desired to adjust the sections 1—2 and 5—6 away from each other, the strap ends are loosened from the buckles, and engaged at a lower point in the length of 60 the said ends, leaving some slack in the straps. The set screws 11 are now loosened and the sections 5—6 are permitted to move away from the section 1—2. When the proper adjustment is secured, the set screws 65 are tightened, after which the slack in the

straps may be taken up. To adjust the section 5—6 toward the section 1—2, the straps are left as they are, and after the adjustment has been made the slack may be taken up.

The improved collar not only permits hames to be dispensed with, but it also may be adjusted to horses of various sizes, thus permitting one collar to be used with different horses.

19 A collar constructed in accordance with the invention is practically indestructible, and it will be understood that the metal shells may be of any desired thickness. It is further understood that minor improvements and changes may be made in order to produce a perfect collar, and to simplify its construction without thereby departing from the principle of my invention.

I claim:

1. A collar of the character specified, comprising a neck section and side sections, the neck section being arched to fit the neck, and the side sections having angular portions at their lower ends to extend beneath the neck, each section consisting of a metal shell open at the inner side, and a tubular casing of flexible material fitting within the shell and extending beyond the shell at the inner side thereof, an inner tube or lining 95 of elastic material having a valve at one end and shaped to fit within the three sections from the free inner end of the angular portion of one side section through the other side section to the free end of the angular portion, the valve extending beyond the adjacent section to permit the tube to be inflated, a strap secured to the front of the shell on the neck section and having its ends free, buckles on the shells on the side sections for engaging the ends of the strap, the free edge of the shell of each side section at the front of the section having an integral tubular bead extending the full length thereof and open at the top of the section, 100 a tubular pin rigid with each end of the section and engaging the upper end of the adjacent bead, set screws threaded through the bead to engage the pin to prevent movement thereof with respect to the bead, and a connection between the lower end of the side sections for drawing them toward and from each other.

2. A collar of the character specified, comprising a neck section and side sections, the neck section being arched to fit the neck, and the side sections having angular portions at their lower ends to extend beneath the neck, each section consisting of a metal shell open at the inner side, and a tubular 120 casing of flexible material fitting within the shell and extending beyond the shell at the inner side thereof, an inner tube or lining of elastic material having a valve at one end and shaped to fit within the three sections 125 130

from the free inner end of the angular portion of one side section through the other side section to the free end of the annular portion, the valve extending beyond the adjacent section to permit the tube to be inflated, a strap secured to the front of the shell on the neck sections and having its ends free, buckles on the shells on the side sections for engaging the ends of the strap, 10 a sliding connection between each end of the neck section and the upper end of the adjacent side section, and a connection between the lower ends of the side sections for moving them toward and from each other.

15 3. A collar of the character specified, comprising a neck section and side sections, the neck section being arched to fit the neck, and the side sections having angular portions at their lower ends to extend beneath the neck, 20 each section consisting of a metal shell open at the inner side, and a tubular casing of flexible material fitting within the shell and extending beyond the shell at the inner side thereof, an inner tube or lining of elastic 25 material having a valve at one end and shaped to fit within the three sections from the free inner end of the angular portion of one side section through the other side section to the free end of the angular portion, 30 the valve extending beyond the adjacent section to permit the tube to be inflated, the shell of each side section having at one edge an integral bead extending the full length of the said edge and open at the top, a pin 35 rigid with each end of the neck section and engaging the upper end of the bead of the adjacent side sections, set screws threaded through the bead into engagement with the pin, and adjustable connections between each

side section and the neck section for holding 40 the said sections during adjustment.

4. A collar of the character specified, comprising a neck section and side sections, the neck section being arched to fit the neck, and the side sections having angular portions at their lower ends to extend beneath the neck, 45 each section consisting of a metal shell open at the inner side, and a tubular casing of flexible material fitting within the shell and extending beyond the shell at the inner side thereof, an inner tube or lining of elastic material having a valve at one end and shaped to fit within the three sections from the free inner end of the angular portion 50 of one side section through the other side section to the free end of the angular portion, the valve extending beyond the adjacent section to permit the tube to be inflated, the shell of each side section having 55 at one edge an integral bead extending the full length of the said edge and open at the top, a pin rigid with each end of the neck section and engaging the upper end of the bead of the adjacent side sections, and set screws threaded through the bead into engagement with the pin.

5. A collar of the character specified, comprising an arched neck section and side sections, each side section having an angular portion at its lower end, and each section 70 consisting of a rigid shell open at its inner side, and a casing of flexible material filling the shell and extending beyond the shell at the open side, an inflatable inner tube filling the casings of the three sections, and a 75 slideable connection between the neck section and the side sections.
